CARBONIZING PROCESS

Filed Sept. 22, 1924

UNITED STATES PATENT OFFICE

EDWARD A. DIETERLE, OF GLENN ELLYN, ILLINOIS

CARBONIZING PROCESS

Application filed September 22, 1924. Serial No. 739,051.

My invention relates more particularly to a process of carbonizing comminuted or powdered coal or other carbonaceous material in a continuous manner; the main object being to provide a method involving a continuous process of carbonization of coal from a gas making or gas enriching standpoint, while at the same time enabling the production of a cheap coke or smokeless fuel; the method being such that both low and high temperature carbonization are possible.

My invention is preferably carried out by the use of apparatus comprising a vertical retort, wherein either low or high temperature carbonization are possible, arranged and constructed to receive powdered or suitably comminuted coal, which is fed or sprayed into the apparatus with the aid of any suitable gaseous medium or steam; preferably by means of the gas to be enriched; the apparatus permitting continuous operation and carbonization and the production of a cheap coke or smokeless fuel.

The objects and advantages of my invention will be more fully comprehended from the detailed description of the accompanying drawing, which illustrates apparatus especially adapted for my improved method, wherein:

Figure 1 is a vertical sectional view with intermediate portions broken away.

Figure 2 is a cross section taken substantially on the line 2—2 of Figure 1.

In the particular exemplification of the invention, as shown in the drawing, I disclose a pair of retorts 10 and 11, arranged one above the other in communicating relation and surrounded by a suitable outer casing or wall 12 in proper spaced relation with the retorts for conveying the heating gases or products of combustion which come from the furnace 13, into intimate contact with the retorts.

The upper retort is preferably of heat resisting metal, although it may be made of refractory material; and while the lower retort is shown as preferably of refractory material, suitable heat resisting metal may also be employed.

The outer casing 12 and the furnace 13

are preferably made integral as shown and provided with the producer gas passage or inlet 14 for conveying the hot gases into the chamber 15 which surrounds the retorts 10 and 11; the hot gases or products of combustion being caused to travel in a circuitous path around the retorts by means of suitably arranged baffles 16. The outer casing 12 is shown preferably provided with an air passage 17 communicating at the lower end with the chamber 15 by means of a suitable number of ports 18; while the casing at points diametrically opposite the ports 18 is shown provided with suitable ports or sight openings 19, (having proper closures) whereby to observe the nature of the flame within the chamber 15.

The secondary air passage 17 is shown leading from the upper end of the casing 12, where it communicates with a suitable recuperator or air preheater 20, by means of passage 21. The recuperator or preheater comprises a properly lagged shell having diaphragms or partitions 22, 23 adjacent to opposite ends of the shell suitably connected with the outer shell so as to divide the shell into separate compartments or portions for the products of combustion and the secondary air. The end of the shell 20, adjacent to the main casing 12, communicates with the chamber 15 by passage 24, and the products of combustion are caused to pass through the tubes or conduits 25 and are delivered at the diaphragm 23 at the opposite end of the recuperator which connects with the flue or stack.

The recuperator is provided with a suitable inlet 26 whereby air enters the shell and is caused to pass in a more or less circuitous manner around the tubes 25 by means of baffles 27; with the result that the secondary air is preheated before it enters the passage 17.

The upper end of the retort 11 is shown provided with a cap or top 28, through which the lower end of the upper retort 10 extends; while the upper end of retort 10 extends through the outer casing 12 and is provided with a head 29 which is shown provided with a valved conduit 30. The conduit 30 may be

connected with a suitable source of air supply or other proper medium; and this conduit has a valved connection 31 which may connect with the supply of gas to be enriched or with a steam supply; the connection 31, in turn, being shown provided with a valved pipe or line 32 which is shown centrally located at one end in a nozzle or sprayer 33 which enters the head 29. One side of the sprayer 33 is provided with suitable feed mechanism and hopper at 34 for introducing the pulverized or comminuted coal into the nozzle; the feed mechanism being operated in any suitable manner from a source 15 of power.

The retorts 10 and 11 are shown preferably flaring toward the lower ends in order to prevent any possibility of the fuel clogging or becoming wedged therein and therefore ensures the fuel dropping down to the bottoms of the retorts.

The lower retort 11, adjacent to its upper end and at a point above the lower end of the upper retort 10, is provided with a gas outlet 35, which may connect with a suitable storage or gas cleaning apparatus; the lower end of the upper retort 10 being smaller than the upper end of the lower retort 11 so as to leave a surrounding chamber for the rising 25 gases and to permit the latter to flow out through outlet 35.

The casing 12 about the lower end of retort 11 is shown dished and provided with an outlet 36 and suitable discharging mechanism as at 37, as well as a suitable closure 35 as at 38, whereby the coke may from time to time be withdrawn from the retort or continuously be removed therefrom after the apparatus is in operation and the process 40 is being carried out. This outlet 36 is also shown provided with a pipe 37^a which may connect a steam supply, thus enabling steam to be introduced for the purpose of quenching the coke before it discharges from the 45 retort, and at the same time increase the gas production due to decomposition of the steam or a portion thereof under certain temperature conditions.

The head 29 of the upper retort 10 is also 50 shown provided with a normally closed opening 39 for the purpose of introducing a test rod whereby to determine the normal or working coke level in the lower retort; the normal coke level being shown for example in dotted 55 lines in the lower retort at 40.

In practice, the furnace 13 being in operation, the pulverized coal or comminuted material is supplied to the hopper portion of the feed mechanism 34 and the finely divided material or coal is introduced into retort 10 by the nozzle 33 by means of steam or other gaseous medium. The operation of the nozzle causes the finely divided or pulverized coal to be thrown into contact with 60 the heated walls of the upper retort, thereby

inducing distillation of the coal and produces a partial conversion into coke; the liberated gas as well as the small partially coked particles passing out through the lower end of the upper retort 10. The small particles of coke 70 are allowed to agglomerate in the lower retort until the proper working level is reached, as shown for example at 40 and the agglomerated mass subjected to further coking which cements the particles together to form a coke; while the gas flowing out of the lower end of retort 10 flows into the upper chamber or 75 end of retort 11 and passes out through the gas outlet 35.

After the proper working level in lower 80 retort 11 has been reached, the coke discharging mechanism in the discharge 36 is set in operation and the coke is removed from retort 11 at any desired speed depending upon the rate of feed of the powdered coal into 85 the upper retort 10, as well as the amount of volatile matter desired left in the coke.

After the proper working coke level has been determined and ascertained by means of a test rod inserted through the normally 90 closed opening 39, and the rate of powdered coal feed and coke discharge have been synchronized, the working level will be maintained and opening 39 may remain closed.

When desired, the gas to be enriched, may 95 be employed for spraying the powdered coal or material into the upper retort 10; and when desired steam may be introduced by pipe 37^a into the coke receiving or lower retort 11, so as to assist in cooling the coke.

With my invention, coking coal is carbonized continuously and rapidly. By practicing the method with apparatus as disclosed the coking is accomplished more rapidly than in the ordinary retort or coke oven systems, 105 because the heat is very rapidly transferred to the fine particles of coal and also to the agglomerated coke particles in the lower retort. In systems as heretofore employed, the heat was caused to travel through the 110 outer layer or shell of coke before it could reach the inner core or shell of undistilled coal.

In the practice of my invention, the rich volatile matter is rapidly distilled off in the 115 upper retort; while the lean volatile matter remaining in the coke, still containing cementing material, although given a longer time for distillation in the lower retort, is nevertheless rapidly carried on; with the result that the total time for both operations is materially less than necessary in the usual apparatus for coal carbonization. As a result, coke can be produced in a minimum period of time; and blue water gas, or other 120 gases can be enriched. The rich gases which distill off in the upper retort are not subjected to excessive high temperatures as in the ordinary processes where they are made to pass through the hot coke and consequently 125 130

are partly decomposed into gases of lower molecular weight with a deposition of free carbon in the coke.

My improved process is preferably employed for combination low and high temperature carbonization; the upper retort being maintained at a lower temperature than that of the lower retort where the coking is completed; and the rich gases issuing from the bottom of the upper retort are caused to mix with the lean gases emerging from the lower retort, to form a volume of gas which will contain more heating value per pound of coal carbonized than is true with the gases resulting from the systems at present in use.

What I claim is:

1. The method of producing an enriched gas and coke from coal in a vertical substantially air-tight chamber having upper and lower portions and heated entirely externally, the lower portion being heated higher in temperature than the upper portion and having an outlet for the gas at an intermediate point between the upper and lower portions which consists in spraying fine particles of coking coal into the upper part of the externally and entirely heated substantially air-tight chamber where partial coking is obtained substantially instantaneously, allowing the partially coked heated particles to agglomerate in the more highly heated lower part of the chamber to a predetermined level below said upper part to provide a gas space where the agglomerated mass is subjected to further heating, combinedly withdrawing, at a point intermediate of the point of introduction of the coal particles and the level of the agglomerated mass, the rich and lean gases resulting from the carbonization in the upper and lower portions of the heated chamber, and intermittently withdrawing the coke from the lower portion, after said agglomeration reaches the predetermined level.
2. The method of producing an enriched gas and coke from coal in a vertical substantially air-tight chamber having upper and lower portions and heated entirely externally, the lower portion being heated higher in temperature than the upper portion and having an outlet for the gas at an intermediate point between the upper and lower portions which consists in spraying fine particles of coking coal by means of a combustible gas into the upper part of the externally and entirely heated substantially air-tight chamber, allowing the heated particles to agglomerate in the lower more highly heated portion of said chamber to a predetermined level below said upper part so as to provide a gas space, further heating the agglomerated mass, withdrawing the rich and lean gases from the upper and lower portions of said chamber at an intermediate point above the level of the agglomerated mass, and intermittently remov-

ing the coke from the bottom of the agglomerated mass.

3. The method of producing an enriched gas and coke from coal in a vertical substantially air-tight chamber having upper and lower portions and heated entirely externally, the lower portion being heated higher in temperature than the upper portion and having an outlet for the gas at an intermediate point between the upper and lower portions which consists in spraying fine particles of coking coal into the upper part of the externally and entirely heated substantially air-tight chamber, introducing a combustible gas adjacent to the point of introduction of said particles, allowing said gas to flow in the direction of said particles, allowing the heated particles to agglomerate in the lower part of the heated chamber to a predetermined level below said upper part so as to produce a gas space, subjecting the agglomerate mass to a further heating, and combinedly withdrawing the mixed gas resulting from the introduced gas and the carbonization in the upper and lower portions of the entirely heated chamber at a point adjacent to the level of the agglomerate mass of coke.

EDWARD A. DIETERLE.
